UNITED STATES PATENT OFFICE.

HARRY A. WEBB, OF HAMDEN, CONNECTICUT.

TOY VEHICLE.

1,243,465.

Specification of Letters Patent. Patented Oct. 16, 1917.

Application filed February 19, 1917. Serial No. 149,504.

To all whom it may concern:

Be it known that I, HARRY A. WEBB, a citizen of the United States, residing in Hamden, in the county of New Haven and 5 State of Connecticut, have invented certain new and useful Improvements in Toy Vehicles, of which the following is a full, clear, and exact description.

This invention relates to toys, and more 10 particularly to toy vehicles for rather young children.

There are at present in use certain wheeled toys made to represent horses and the like, that are straddled by the child and propelled by his legs, which are given sort of 15 a walking motion.

One of the objects of the present invention is to provide a toy vehicle which will be of more interest to children than the kind 20 above mentioned, because the horse or other animal has movable legs, which engage the ground or floor and can be actuated to propel the vehicle. This movement can be transmitted to the legs by imparting a rocking, 25 bouncing or other movement to a suitable body mounted on a wheeled base, the propulsion of the vehicle being effected by a body movement of the rider, which can be easily performed and continued for some 30 time without fatigue.

Another object of the invention is to furnish a toy vehicle which can be readily steered and controlled and can make good 35 progress over the ground by a leg motion generally simulating that of a horse or other animal.

The invention also has in view the general improvement in construction and operation 40 of devices of the class to which the invention relates.

To these and other ends, the invention consists in the novel features and combinations of parts to be hereinafter described and claimed.

45 In the accompanying drawings,

Figure 1 is a side elevation of a child's horse embodying my invention;

Fig. 2 is a similar view, showing the device in another position;

50 Fig. 3 is a top plan view of the device;

Fig. 4 is a front end view thereof;

Fig. 5 is a section on line 5—5 of Fig. 1; and

55 Fig. 6 is a fragmentary plan view of a portion of the base.

In constructing the toy, I use a wheeled

base which preferably includes an elongated longitudinal member 10 having front and rear axles 11, 12 respectively, on which suitable small wheels or rollers 13 are 60 mounted. The front axle or cross bar 11 is longer than the rear axle, and is swiveled to the forward end of the base by a bolt 14 so that the axle or bar is free to turn for steering the vehicle. The base 10 is 65 shown as comprising spacing parallel strips 15 which are set in notches at the centers of the respective cross pieces or axles, the notch 16 in the front cross piece or axle 11 being sufficiently wide to permit the axle or 70 cross piece to turn to the required extent. Intermediate of the ends of the base, an upright support or standard 17 is provided, which is preferably mounted on the base by being interposed and secured between 75 the spaced strips 15, as shown in Fig. 6. In the embodiment shown, the support or standard 17 serves as a mounting for a body 18, which simulates the body of a horse, and is mounted on the standard or support in 80 such a manner as to rock up and down thereon. In the example shown, the standard 17 is in the form of a board, which extends upward into a cut out part 19 in the lower central part of the body 18, which body is 85 also formed of a board; and the body is pivoted to the support by means of cheeks 20 applied to the opposite faces of the body at its intermediate portion and abutting opposite faces of the standard. A pivot bolt 90 21 or other suitable pivot member passes through registering perforations in the cheeks 20 and in the support 17 and permits the body 18 to be rocked on the support to a certain limited extent. This rocking 95 movement of the body is limited by the shape of the cut away portion 19, the sides of which are inclined so as to limit the up-and-down swing of the body in both directions. Mounted on top of the body 18 is a 100 suitable seat 22. In the example shown, this seat is made of wood and is nailed to the upper edge of the body, and the upper edges of the cheek members 20, and a head 23, representing the head of a horse, is fastened 105 to the forward part of the seat member which extends over the forward part of the body at the upper edge thereof.

The vehicle is propelled over the ground by means of one or more legs actuated from 110 the body and engaging the ground or floor. In the example shown, the body has a rock-

ing movement, but this is not always essential. In the example now being described, the body is provided with a pair of legs at the front of the same, and another pair of legs at the rear, these legs being suitably pivoted to the body at their upper ends. The front legs 24, 25 are pivoted to the body by means of a bolt 26 located near the forward end of the body, one leg being located at one side of the body and the other at the opposite side thereof. One of these legs is at one side of the base 10, and the other at the opposite side thereof, and the legs are suitably spaced apart at their upper ends by means of blocks 27 held in place by the bolt 26 and located at opposite faces respectively of the body, and between the body and the respective legs. These spacing blocks 27 preferably have curved outer faces adjacent to or abutting the inner faces of the legs, so that the legs can have a certain amount of lateral play in turning corners, as hereinafter explained. The swinging movement of the body relatively to the base is so restricted that the legs 24, 25 always assume an inclined position, that is, they are always inclined relatively to a horizontal plane and their lower ends engage the floor or ground somewhat to the rear of the pivotal point of support 26. These legs may be advantageously made of wood boards cut to about the shape shown, and in fact, all of the main parts of the device may be readily cut from fairly thin wood boards, so that the device can be produced at low expense. Another pair of legs 28, 29 similar to the legs 24, 25 is provided at the rear of the body. The legs of the latter pair are pivoted to the body by a bolt 30 adjacent the rear edge of the body. The lower ends of these rear legs are located to the rear of the base 10, and therefore they can be placed closer together than the legs 24, 25, but the rear legs are preferably spaced apart by means of curved spacing blocks 31, generally similar to the blocks 27 but not so thick. Both legs, as well as both spacing blocks, are held in place by one bolt, and the construction may therefore be readily assembled and taken apart.

Supposing the parts to be in the position shown in Fig. 1, the vehicle can be propelled forwardly by producing a downward movement of the forward end of the body 18. This is produced by the child, who straddles the body, sitting on the seat 22 and placing his feet on the cross piece 11 so as to steer, the hands being placed on the handle pieces 32 at opposite sides of the head. If now the body be rocked forwardly and downwardly, the legs 24, 25 will be forcibly pushed against the ground or floor, and the reaction will be such as to advance the vehicle, causing it to roll forward on its wheels 13. It will be observed that the leg 24 is

shorter than the leg 25. In this way, the longer leg is caused to take hold first and in a gradual manner, and then, as the downward movement of the forward end of the body is continued, the shorter leg 24 becomes effective and continues the propulsive effect. When the body is rocked rearwardly, the vehicle is advanced by the rear legs 28, 29, which act in substantially the same manner as the front legs. The rear leg 28 is shorter than the rear leg 29 and takes hold after the leg 29 has begun its pushing action. In the example shown, both of the short legs are located at the same side of the horse, and both of the long legs are at the opposite side, but obviously this is not essential. The lower ends of the legs are preferably provided with rubber tips 33, so that the device may be used indoors without injuring the floor. It will be understood that by rocking to and fro on the body fairly rapidly, the child can push the vehicle forward very quickly by a series of intermittent pushing movements produced by the set of legs. By making the legs of different lengths, as described, the pushing effort is distributed, and in the case illustrated four different pushing impulses are obtained by rocking forward and then backward, so that a very uniform and positive propulsion is produced.

In the example illustrated, the body is normally held in an intermediate position with respect to the amplitude of its swinging movement by means of front and rear springs 34, 35 respectively which connect the front and rear ends respectively of the body 18 with the base. As the forward end of the body is moved downward, the rear spring is tensioned, and consequently when the rider swings the body backward, the tensioned rear spring will aid in depressing the rear end of the body and actuating the rear legs. Similarly, when the body is thrown forwardly, the tensioned front spring aids in depressing the forward end of the body and actuating the front legs. These springs, in other words, are useful to a certain extent in controlling the movement of the body 18, but they may be dispensed with in some instances.

In turning corners, the front cross piece 11 is turned to one side or the other by the feet of the child, and the spacing members 27 permit the lower ends of the front legs to be displaced laterally to the required extent. As the child holds onto the handle members 32, there is no difficulty in holding the feet on the front crosspiece for steering, and no tendency for the child to fall or become displaced in swinging the body for driving the legs.

Various changes may be made in the details of the construction without departing from the scope of my inventive idea. I do

not limit myself to a device in which four propelling legs are employed, nor do I limit myself to a construction in which the legs are of different length, nor to one in which the driving movement of the leg or legs is produced by a rocking movement of the body, as distinguished from some other body movement. Changes may be made in these and other details without departing from the invention as defined in the claims.

What I claim is:-

1. In a toy vehicle, the combination of a wheeled base adapted to roll over the ground, a body mounted on the base and movable relatively thereto by a body movement of a child seated on said body, and a propelling member attached to and movable with said body and engageable with the ground to propel the vehicle; substantially as described.

2. In a toy vehicle, the combination of a wheeled base member having a wheeled cross piece for steering, a body mounted on said base member but movable relatively thereto by a body movement of a child seated on said body, and a propelling leg carried by and movable with the body and engaging the ground; substantially as described.

3. In a toy vehicle, the combination of a wheeled base, a body movably mounted thereon, and a propelling leg pivoted to the body and engaging the ground so as to roll the vehicle forward as said body is moved; substantially as described.

4. In a toy vehicle, the combination of a rolling base, a body mounted to swing up and down thereon by movement of a child seated on said body, means for steering the vehicle by the legs of the child, and propelling legs pivoted to said body and movable therewith, and engaging the ground to roll the vehicle forward; substantially as described.

5. In a toy vehicle, the combination of a wheeled base, a body movably mounted on said base and simulating the body of an animal, and a propelling leg simulating the leg of an animal attached to said body and movable therewith and engageable with the ground or floor to push the vehicle forward as the body is moved relatively to the base; substantially as described.

6. In a toy vehicle, the combination of a wheeled base, a body movable thereon, and a pair of propelling legs at opposite sides of the body pivoted thereto and engageable with the ground to roll the vehicle forward as the body is moved relatively to the base; substantially as described.

7. In a toy vehicle, the combination of a wheeled base, the body movable relatively thereto by movement of a child seated on said body, and a pair of propelling legs secured to said body and movable therewith

and engageable with the ground, one of said legs longer than the other to distribute the pushing effort; substantially as described.

8. In a toy vehicle, the combination of a rolling base, a rocking body mounted thereon simulating the body of an animal, and propelling legs secured to and depending from said body and engaging the ground and simulating the legs of an animal, said legs constructed and arranged to roll the vehicle forward as the body is moved relatively to the base; substantially as described.

9. In a toy vehicle, the combination of a wheeled base, a seat member movably mounted thereon, and a propelling leg movably connected with the seat member and adapted to engage the ground; substantially as described.

10. In a toy vehicle, the combination of a wheeled base, a seat member movably mounted thereon, and a pair of propelling legs movably connected with the seat member and adapted to engage the ground to roll the vehicle forward; substantially as described.

11. In a toy vehicle, a wheeled base member, a seat member, means connecting the seat member and base member for relative movement, and a propelling leg connected with the seat member in front of its connection with the base; substantially as described.

12. In a toy vehicle, a wheeled base member, a seat member, means connecting the seat member and base member for relative movement, and a propelling leg connected with the seat member at the rear of its connection with the base; substantially as described.

13. In a toy vehicle, the combination of a rolling base, a seat member, means of connection between the seat member and base, whereby the seat member is mounted to swing up and down relatively to the base, and a propelling leg connected with the seat member remote from its connection with the base and adapted to engage the ground to roll the vehicle forward; substantially as described.

14. In a toy vehicle, the combination of a rolling base, a body member movably mounted thereon, a seat mounted on top of said body member, a propelling leg movably connected with said body member and adapted to engage the ground, and a handle disposed on opposite sides of the body member; substantially as described.

15. In a toy vehicle, the combination of a rolling base having a swiveled front axle, a body member, means for connecting said body member movably with said base, a seat on said body member, and a propelling leg pivoted to the body member at the rear of the connection of said body member with the base; substantially as described.

16. In a toy vehicle, a movable base, a body mounted to move up and down thereon and

having a seat portion adapted to be straddled by the child, a head mounted on said body, and a propelling leg pivoted to the body and inclined downwardly and rearwardly therefrom and adapted to engage the ground as the body swings up and down to propel the vehicle; substantially as described.

17. In a toy vehicle, a wheeled base, including a swiveled axle for steering, a body having a seat, means for connecting said body with the base so that the body can swing up and down, a handle carried by the body, and a downwardly and rearwardly inclined propelling leg pivoted to the body to engage the ground rearwardly of said base; substantially as described.

18. In a toy vehicle, a movable base, a body movably mounted thereon and having a seat, and a propelling leg pivoted to the body and engaging the ground at the rear of the base; substantially as described.

19. In a toy vehicle, a wheeled base having a swiveled steering axle, a body, a seat carried by the body adapted to be straddled by the child, means for connecting the body with the base so that the former may have an up and down swinging movement, a head carried by the body, a handle projecting laterally from the head, and one or more propelling members depending from the body and engaging the ground; substantially as described.

20. In a toy vehicle, a wheeled base having a swiveled steering axle, a body, a seat carried by the body adapted to be straddled by the child, means for connecting the body with the base so that the former may have an up and down swinging movement, a head carried by the body, a handle projecting laterally from the head, and one or more propelling members depending from the body and engaging the ground, said wheeled steering axle being so located relatively to the seat as to permit the child to steer the vehicle with his feet; substantially as described.

21. In a toy, the combination of a base structure movable over the ground, a seat member located above the base structure, means for mounting said seat member movably on the base structure, and a propelling

leg connected with said seat member and adapted to engage the ground to propel the device; substantially as described.

22. In a toy, the combination of a base structure movable over the ground, a seat member, means mounting said seat member on the base structure so that the former is movable up and down by a body movement of a child seated on said seat member, and a propelling leg movably connected with said seat member at its upper end and engaging the ground at its lower end, said leg normally having an inclined position; substantially as described.

23. In a toy, the combination of a base structure movable over the ground, a seat member located above the base, means for mounting said seat member on the base, so that the former is movable up and down by a child occupying said seat member, a handle member connected with said seat member, and a rearwardly inclined propelling leg pivotally connected with the seat member and engageable with the floor or ground; substantially as described.

24. In a toy, the combination of a rolling base, a seat member adapted to seat a child, movably mounted on said base to move up and down, a head secured to said seat member and having a handle associated therewith, and a propelling leg operatively connected with said seat member and engageable with the floor or ground; substantially as described.

25. In a toy, the combination of a wheeled base, a propelling leg to engage the ground, and propel said base, a body movably mounted on the base and connected with said leg to operate the same, and means for returning said body to a predetermined position after it has been moved to actuate said leg; substantially as described.

26. In a toy, the combination of a rolling base, a body movably mounted thereon, a leg pivoted to said body and engageable with the ground to propel the device, and yielding means normally holding the body in a predetermined position; substantially as described.

In witness whereof, I have hereunto set my hand on the 17th day of February, 1917.

HARRY A. WEBB.
